UNITED STATES PATENT OFFICE.

CHARLIE E. HUFF, OF DAYTON, OHIO.

COMBINATION LOCK.

1,403,783.

Specification of Letters Patent. Patented Jan. 17, 1922.

Application filed June 12, 1919. Serial No. 303,675.

To all whom it may concern:

Be it known that I, CHARLIE E. HUFF, a citizen of the United States, residing at Dayton, in the county of Montgomery and State of Ohio, have invented certain new and useful Improvements in Combination Locks, of which the following is a specification, reference being had therein to the accompanying drawing.

10 This invention relates to combination locks, and has for its particular object to provide an improved combination lock suitable for use as an anti-theft device for automobiles, or for controlling electrical circuits of any kind, such as lighting circuits, or signal circuits.

In one form my invention is here shown as applied to the battery and ignition system of an automobile, the specific arrangement of the application of the invention being for illustrative purposes only, and it will be understood that various modifications can be made thereof without departing from the underlying principle and the spirit of the invention.

As applied to automobiles, the invention is directed to the solution of the problem of preventing unauthorized use and theft of automobiles. In this respect the present lock is an improvement over various other types of locks and anti-theft devices which are now extensively used in view of the common and growing practice of stealing or temporarily appropriating automobiles.

35 As here shown my approved lock is connected to the battery and ignition circuit of an automobile in such a manner that both the battery and ignition circuits may be controlled.

40 The lock consists of a plurality of combination number disks cooperating with a lock barrel, and a lock stem which controls the circuit contacts, there being in the preferred form of the lock as here shown, also a dial and a pointer cooperating therewith to indicate the "on" and "off" positions of the switch.

50 The number disks of the locks may consist of two or more disks used in combination, disks of different diameters being used preferably to enable more ready manipulation thereof. In the preferred form the disks are provided with peripheral bands in which the numerals 0 to 9 are formed, each band being adjustable to ten operable positions relative to a fixed point on the disk.

Thus two disks used in combination are capable of adjustments to effect one hundred different combinations, and three disks to effect one thousand different combinations. 60 By this arrangement the owner or operator of a machine may effect a change of combination in the lock at will by adjusting one or more of the disks.

In the accompanying drawings: 65
Fig. 1 is a side elevation of the complete lock;

Fig. 2 is a longitudinal cross section of the same, taken substantially through the center thereof; 70

Fig. 3 is a detailed view of the lock casing and barrel;

Fig. 4 is a plan view of the inner end of the lock casing showing the manner of arranging the electrical contacts relative to 75 the adjustable lock stem;

Fig. 5 is a detailed view of the lock stem;

Fig. 6 is a detail of one of the combination number disks; 80

Fig. 7 is a cross sectional view of the number disk shown in Fig. 6.

Referring to the drawings, the lock casing consists preferably of a hollow cylindrical extension 1 in which the electrical contacts 85 are supported, the lock barrel 2, base or partition wall 3 and a mounting flange 4, intermediate the cylindrical extension and the barrel, by means of which the casing may be attached in any suitable manner to 90 the instrument board, or other suitable part of an automobile, the outer face of the flange, as here shown, being used as an indicator dial 6 upon which the positions of the lock stem 7 relative to the electrical contacts may be indicated. 95

The lock barrel 2 has a longitudinal aperture 8 extending therethrough in which the stem 7 is slidably and rotatively mounted. Extending longitudinally in the lock barrel 100 and through the base wall 3 of the casing, and communicating with the longitudinal aperture 8 is a slot 9 and communicating therewith laterally in one direction are parallel slots 10. The stem 7 is provided with 105 radially extending pins 11 arranged in longitudinal alignment with the slot 9 when the stem is in a position to be moved longitudinally in the barrel and adapted in one longitudinal position of the stem to register with the slots 10 when the stem is rotated, the pins being equal in number to 110

the slots, and adapted in another longitudinal position to contact with the wall of the barrel adjacent the slot 9 to prevent rotative movement of the stem in the opposite direction. The stem 7 is provided with a suitable knob or finger hold 7^a by means of which it may be readily adjusted to the various longitudinal and rotative positions, and is further provided with a pointer 7^b 10 secured to the stem by an angularly shaped part thereof as illustrated which admits of relative longitudinal motion but no relative rotary motion, and the pointer is operated through a slot 3^a in the partition 3 to indicate the several positions of the stem on the dial 6.

The inner end of the lock stem 7, within the cylinder 1, is provided with a head of insulating material 12 which is secured to 20 the stem by means of a suitable lock nut 13. Secured in the end of the insulating material is a contact element 14 which cooperates, respectively, when the stem 7 is rotated, with contacts 15 and 16, secured 25 in a suitable mounting of insulating material 17, which may be supported in any suitable manner in the cylinder 1. The contacts 15 and 16 are secured to the mounting 17 by the usual terminal posts 18 and 30 wires 19 and 20 serve to connect the posts and the respective contacts to the battery and ignition circuits.

The combination number disks consist of a body portion 21 having a concentric depression 22 formed therein and an aperture 23 extending through the remaining portion thereof, thus forming at the bottom of the depression an annular flange 24 having a slot 25 therein. One face 26 of the disk is 40 substantially flat, the opposite face 27 having a raised portion 28 formed therein which acts to space one disk from another as the disks are assembled on the lock stem.

In the periphery of the disks a groove 29 45 is formed, and a detachable rim or band 30 is adjustably secured thereover. Set screws 31 cooperate with the groove 29 to hold the bands in any adjusted position on the disk, the band having the numerals 0 to 9 formed 50 in its periphery.

When the number disks are assembled on the barrel 2, the disk of largest diameter is preferably placed adjacent the partition wall 3 and the disk of smallest diameter 55 farthest removed therefrom, such arrangement of the disks being the most convenient for manipulation thereof to effect locking and unlocking adjustments.

When the number disks are in normal relation with the barrel 2 the slot 25 of each disk will be in alinement with the longitudinal slot 9 and the depression 22 of each disk will be in alinement with one of the slots 10. Thus, when the lock stem 7 is 60 moved longitudinally in the barrel the pins 65

11 will pass freely through the slot 9 and the slots 25 and when the stem is rotated in its inner position to effect the "on" and "off" positions thereof relative to the contacts 15 and 16 the ends of the pins projecting above the barrel will move freely through the depressed spaces 22 of the disks without affecting their position on the barrel.

In the above described position of the parts the lock stem may be freely rotated through a limited arc to effect the respective contacts and the neutral position of the stem. Also, in such position of the parts the stem 7 may be drawn outwardly in the lock barrel to move the contact element 14 out of the plane of operative relation with the contacts 15 and 16, until each pin 11 registers with the space 22 of the adjacent disk. The alinement or combination of the lock may then be thrown-out or changed by rotating one or more of the disks on the barrel, thus serving to effectually render the switch and the electrical circuits which it controls inoperative until the disks are again moved into proper alinement, as determined by the particular combination to which the lock is adjusted, when the lock stem may again be moved to its inner position and rendered operative as above described relative to the contacts 15 and 16.

From the foregoing detailed description the construction and operation of my improved lock will be readily understood. It will be observed that the lock may be applied, as here shown, for controlling one or more electrical circuits and thus be doubly effective as an anti-theft device, as the use of supplemental wire connections commonly practised by automobile thieves is thus rendered impossible or at least impracticable.

The lock is of simple substantial construction and is not likely to be rendered out of adjustment by use or tampering thereof. The wide range of combination adjustments 110 that may be made of the locks by individual owners or operators affords ample protection against incidental or accidental knowledge that may be obtained relative to any combination used, as the combination may 115 be conveniently changed as desired by the operator, thus rendering the locks as effective for their use as the most effective combination locks used generally.

The number bands 21 are made to fit the body of the combination disks closely to cause the disks to rotate on the lock barrel 2 as an integral part irrespective of the set screws 31. Thus in either the in or out position of the stem 7 it will be impossible to effect a change in the position of the number bands relative to the central or supporting portion of the disk. To change the combination, it is necessary to know the combination to which the lock is set, then the 120 125 130

stem 7 may be moved to an intermediate point in the longitudinal slot 9, thereby locking all of the number disks against rotative movement, and thus enabling adjustment of the number bands to effect a change in the combination, the set screws 31 serving to prevent accidental displacement of the number bands relative to the inner disk. This arrangement serves to prevent tampering 10 of the lock by individuals not knowing the combination.

Having thus fully described my invention, what I claim as new and desire to secure by Letters Patent, is:—

15 1. In a circuit controlling lock, the combination, with an electrical circuit, of a circuit maker and breaker adjustable rotatably to effect "on" or "off" relations with said circuit, and adapted to be moved longitudinally to a position of inoperative relation therewith, a plurality of disks cooperating with said member and adjustable relative thereto to lock the same in said inoperative position.

20 2. In a circuit controlling lock, the combination, with an electrical circuit, of a circuit maker and breaker adjustable rotatably to effect "on" and "off" relations with said circuit, and adapted to be moved longitudinally to a position of inoperative relation therewith, a plurality of disks cooperating with said member and adapted in one position to permit movement of said member out of said position, and in other positions to prevent movement thereof into said position.

25 3. In a circuit controlling lock, the combination, with an electrical circuit, of a circuit maker and breaker adjustable rotatably to effect "on" and "off" relations with said circuit and adapted to be moved longitudinally to a position of inoperative relation therewith, a plurality of disks cooperating with said member and adjustable relative thereto to lock the same in said inoperative position, and numbers on said disks to indicate their positions relative to said member.

40 4. In a circuit controlling lock, the combination, with an electrical circuit, of a circuit maker and breaker adjustable rotatably to effect "on" and "off" relations with said circuit and adapted to be moved longitudinally to a position of inoperative relation therewith, a plurality of disks cooperating with said member and adjustable relative thereto to lock the same in said inoperative position, and numbers on said disks adjustable to various combinations to indicate the positions of the disks relative to said member.

45 5. In a circuit controlling lock, the combination, with an electrical circuit, of a circuit maker and breaker adjustable rotatably to effect "on" and "off" relations with said circuit and adapted to be moved longitudi-

nally to a position of inoperative relation therewith, a plurality of disks cooperating with said member and adjustable relative thereto to lock the same in said inoperative position, and a dial cooperating with said member to indicate the respective positions thereof relative to said connections.

6. In a circuit controlling lock, the combination, with an electrical circuit, of a circuit maker and breaker adjustable rotatably to effect "on" and "off" relations with said circuit and adapted to be moved longitudinally to a position of inoperative relation therewith, a plurality of disks cooperating with said member and adjustable relative thereto to lock the same in said inoperative position, numbers on said disks to indicate their positions relative to said member, and a dial cooperating with said member to indicate the respective positions thereof relative to said connections.

7. In a circuit controlling lock, the combination, with an electrical circuit, of a circuit maker and breaker adjustable rotatably to effect "on" and "off" relations with said circuit and adjustable longitudinally to a position of inoperative relation with said circuit, and a plurality of disks cooperating with said member and adjustable relative thereto to lock the same in said inoperative position.

8. In a circuit controlled combination lock, an apertured member having a longitudinal and a plurality of lateral slots therein, a stem rotatably and longitudinally operable in said aperture to effect a connection in said circuit or to break the same to effect contact with said circuit and having a corresponding plurality of alined projections operable in said longitudinal slot when the stem is moved longitudinally and operable in the lateral slots when the stem is rotated, a plurality of disks mounted on said member and cooperating with said stem whereby in one position of the disks to permit free longitudinal movement of the stem and in other positions of the disks to prevent longitudinal movement thereof.

9. In a circuit controlled combination lock, an apertured member having a longitudinal and a plurality of lateral slots therein, a stem rotatably and longitudinally operable in said aperture to effect a connection in said circuit or to break the same to effect contact with said circuit and having a corresponding plurality of alined projections operable in said longitudinal slot when the stem is moved longitudinally and operable in the lateral slots when the stem is rotated, a plurality of disks mounted on said member and cooperating with said stem whereby in one position of the disks to permit free longitudinal movement of the stem and in other positions of the disks to prevent longitudinal movement thereof, and numbers on

said disks whereby the position of the disks may be determined in which said stem may be moved longitudinally therethrough.

10. In a circuit controlled combination lock, 5 an apertured member having a longitudinal and a plurality of lateral slots therein, a stem rotatably and longitudinally operable in said aperture to effect a connection in said circuit or to break the same to effect 10 contact with said circuit and having a corresponding plurality of alined projections operable in said longitudinal slot when the stem is moved longitudinally and operable in the lateral slots when the stem is rotated, 15 a plurality of disks mounted on said member and cooperating with said stem whereby in one position of the disks to permit free longitudinal movement of the stem and in other positions of the disks to prevent longitudinal movement thereof, and numbers on 20 said disks adjustable to various combinations whereby the position of the disks may be determined in which said stem may be moved longitudinally therethrough.
- 25 11. In a circuit controlled combination lock, an apertured member having a longitudinal and a plurality of lateral slots therein, a stem rotatably and longitudinally operable in said aperture to effect a connection in 30 said circuit or to break the same to effect contact with said circuit and having a corresponding plurality of alined projections operable in said longitudinal slot when the stem is moved longitudinally and operable 35 in the lateral slots when the stem is rotated, a plurality of disks mounted on said member and cooperating with said stem whereby in one position of the disks to permit free longitudinal movement of the stem and in 40 other positions of the disks to prevent longitudinal

tudinal movement thereof, and numbers on said disks whereby the position of the disks may be determined in which said stem may be moved longitudinally therethrough, and a dial cooperating with said stem to indicate 45 the rotative positions thereof.

12. In a circuit controlled combination lock, an apertured member having a longitudinal and a plurality of lateral slots therein, a stem rotatably and longitudinally operable 50 in said aperture to effect a connection in said circuit or to break the same to effect contact with said circuit and having a corresponding plurality of alined projections operable in said longitudinal slot when the 55 stem is moved longitudinally and operable in the lateral slots when the stem is rotated, a plurality of disks mounted on said member and cooperating with said stem whereby in one position of the disks to permit free 60 longitudinal movement of the stem and in other positions of the disks to prevent longitudinal movement thereof, and a dial cooperating with said stem to indicate the rotative positions thereof. 65

13. In a circuit controlling combination lock, a lock barrel and a plurality of disks rotatably mounted thereon, a stem longitudinally and rotatably operable in said barrel to effect connections in said circuit and to break the 70 same to effect contact with said circuit and cooperating with said disks, number bands adjustably secured to said disks, and means to move the said stem to prevent movement of the disks relative to said barrel whereby 75 a change in the combination of said lock may be effected by changing the position of the number bands relative to said disks.
- In testimony whereof, I affix my signature.

CHARLIE E. HUFF.
